His Attorney.

UNITED STATES PATENT OFFICE

MARCUS A. ACHESON, OF SCHENECTADY, NEW YORK, ASSIGNOR TO GENERAL ELECTRIC COMPANY, A CORPORATION OF NEW YORK

ELECTRICAL DISCHARGE DEVICE

Application filed May 19, 1928. Serial No. 279,120.

The present invention relates to electrical discharge devices which are intended to be operated at high impressed voltages. Such devices usually consist of a water cooled anode, a glass tube or sleeve sealed thereto and other parts. The glass portion of such a device frequently becomes overheated and, unless means are taken to prevent it, the seal between the glass and metal portions is apt to be punctured due either to arcing between the different electrodes or to corona discharge. It is one of the objects of my invention to provide means whereby the glass tube in a device of this character may be efficiently cooled and the seal adequately shielded both from arc and corona discharge.

The novel features which I believe to be characteristic of my invention are set forth with particularity in the appended claims. The invention itself, however, will best be understood from reference to the following specification when considered in connection with the accompanying drawing in which Fig. 1 shows a view partly in section and partly in elevation of a discharge device which embodies the features of the present invention; while Fig. 2 is a detailed view on an enlarged scale of the water-cooled anode and shielding means.

The device shown in the drawing comprises a receptacle consisting of a glass tube or sleeve 1 which is sealed to a copper anode 2 at the point 3. Leads 4 and 5 supply current to the cathode electrode, while lead 6 supplies a potential to the grid or control electrode. The anode is provided with a flange 7 and is adapted to be inserted into a water jacket of the type described in my copending application Serial No. 192,429, filed May 16, 1927. This jacket comprises an outer cylindrical member 9 and has a collar 10 at its upper end. The collar is provided with four brackets each of which consists of two members 11 pivoted at their lower ends on a rod 11' and connected rigidly together by a plate 12. The upper ends of the members 11 are connected together by a rod 12' on which an angular member 13 is pivoted, the upper end of member 13 being adapted to engage the flange 7 of the anode 2. The pivoted mem-

bers 13 are provided with screw-threaded bolts 14, the inner ends of which bear against the plates 12 so that when the bolts 14 are rotated in one direction the upper ends of the pivoted members 13 will be forced against the flange 7 to thereby rigidly secure the anode within the water jacket. The jacket is provided with an inner concentric member 15 which is flexibly secured to the base 16 of the jacket by an expandible metal ring member 17.

To remove the discharge device from the water jacket the base portion of the jacket is provided with a metal block 18 having a longitudinally movable part 19 extending through an opening 20 in base 16 and adapted to engage the lower end of the discharge device. An eccentric member 21 is rotatably mounted in the member 19 and secured to a shaft 22 so that rotation of the latter forces member 19 upwardly into engagement with the anode and thus forces the discharge device partly out of the water jacket.

The water jacket is surrounded by a concentric metallic casing 23 which is spaced from the water jacket and provided with flanges or metal spiders 24 and 25 adjacent its upper and lower ends. The water jacket is supplied with a pair of flanges 26 and 27 which are located between and adjacent to the flanges 24 and 25 respectively. Springs 28 and 29 are mounted between the adjacent flanges on the casing and water jacket and serve to flexibly support the discharge device on the casing. The upper end of the casing is enlarged as indicated at 30 and contracted at point 31 which is slightly beyond the seal between the glass tube 1 and metal anode 2. The upper edge of the casing 23 is curved outwardly as clearly indicated in the drawing.

The casing is supported from a base member comprising a hollow insulator 32 which may be made of a phenol condensation product or other suitable means and is provided with a cap portion 33 which may be made of glass or wood or other suitable material. The latter has an opening 34 through which the casing and water-jacketed anode extend.

A steel angle-iron 35 secured to the casing and cap 33 retains the casing in position.

5 A rubber hose 36 is wound around the base portion 32 and connected at 37 and 38 to the inner and outer portions of the water jacket so that cooling fluid will enter at 37 and flow over the top of the inner member 15 and out at the point 38.

10 The base 32 also has an opening 39 through which compressed air may be blown. The air flows upwardly through the casing 23 and the upper end of the casing acts as an air nozzle and directs the compressed cooling air along the outer surface of the glass tube and 15 maintains the latter at a desired relatively low temperature.

20 The casing 23 is electrically connected to the anode through the water jacket and not only serves as an air nozzle to cool the glass portion of the sleeve but also serves to shield the seal between the glass tube and anode from corona and arc discharges between the electrodes of the device. Although I have shown an air inlet at the point 39, such a 25 location is not essential and the air inlet may, if desired, be located at any point in the casing 23 below the contracted portion 31 thereof.

30 What I claim as new and desire to secure by Letters Patent of the United States, is:

1. An electric discharge device comprising a vitreous tube and a hollow metal electrode sealed to said tube, a hollow metal electric discharge shield located externally to 35 and spaced from said discharge device and electrically connected to said electrode, said shield having an open end and extending beyond the junction of said tube and electrode, and means whereby air may be supplied to 40 the space between said shield and electrode and directed through the open end onto the vitreous tube over substantially the entire length.

2. An electric discharge device comprising 45 a vitreous tube and a hollow metal anode sealed to one end of the tube, a hollow metal electric discharge shield surrounding said anode and electrically connected to the anode, said shield having a curved surface 50 at one end thereof opposite the vitreous tube, and means whereby air may be directed through said shield and onto the surface of said tube over substantially the entire length.

55 3. An electric discharge device comprising a container having a glass member and a metal member sealed thereto, the latter member constituting one of the electrodes of the discharge device, a casing surrounding and 60 spaced from said metal member and projecting beyond the junction of said glass and metal members, said casing having an outwardly curved upper end portion constituting an electrostatic shield and having an 65 open end, means whereby air may be di-

rected through said open end portion onto the surface of the glass member.

4. An electric discharge device comprising a container having a glass member and a metal member sealed thereto, the metal member constituting one of the electrodes of the discharge device, a casing surrounding and spaced from said metal member and extending beyond the junction between said metal and glass members, said casing having an open end and serving as an electric discharge shielding member for said junction and as an air nozzle whereby air may be directed through the open end along the surface of said glass tube over substantially the entire length.

5. An electric discharge device comprising a container having a glass member and a metal member sealed thereto, the metal member constituting one of the electrodes of the device, a jacket surrounding and supporting said metal member, means whereby a cooling fluid may be supplied to the jacket, and a casing supporting said jacket and electrically connected to said electrode, said casing being spaced from the jacket and extending beyond the junction of the metal and glass members, the upper end of said casing having an outwardly curved surface.

6. An electric discharge device comprising a container having a glass member and a metal member sealed thereto, the metal member constituting one of the electrodes of the device, a jacket surrounding and supporting said metal member, means whereby a cooling fluid may be supplied to the jacket, a casing supporting said jacket and electrically connected to said electrode, said casing being spaced from the jacket and extending beyond the junction of the metal and glass members, the upper end of said casing having an outwardly curved surface, and means whereby air may be forced through said casing and onto said glass member.

In witness whereof, I have hereunto set my hand this 18th day of May, 1928.

MARCUS A. ACHESON.
